The ornamental design for a soffit panel with short holes, as shown and described.

DESCRIPTION

FIG. 1 is an isometric view of a soffit panel with short holes according to an exemplary embodiment;
 FIG. 2 is a top plan view of the soffit panel with short holes shown in FIG. 1;
 FIG. 3 is a bottom plan view of the soffit panel with short holes shown in FIG. 1;
 FIG. 4 is a bottom-end elevation view of the soffit panel with short holes shown in FIG. 2;
 FIG. 5 is a top-end elevation view of the soffit panel with short holes shown in FIG. 2;
 FIG. 6 is a left-side elevation view of the soffit panel with short holes shown in FIG. 2;
 FIG. 7 is an enlarged detail of FIG. 6; and,
 FIG. 8 is a right-side elevation view of the soffit panel with short holes shown in FIG. 2.
 Broken lines in the drawings indicate environmental structure or boundaries of the vent for a soffit panel with short holes that form no part of the claimed design.
